UNITED STATES PATENT OFFICE.

JOHN HENKEL, OF HOBOKEN, NEW JERSEY, ASSIGNOR TO JOHN MEHL & CO., OF NEW YORK, N. Y.

DESIGN FOR A POCKET-BOOK.

SPECIFICATION forming part of Design No. 21,542, dated May 17, 1892.

Application filed March 17, 1892. Serial No. 425,359. Term of patent 7 years.

To all whom it may concern:

Be it known that I, JOHN HENKEL, a citizen of the United States, residing at Hoboken, in the county of Hudson and State of New Jersey, have invented and produced a new and original Design for a Pocket-Book, of which the following is a full, clear, and exact description, reference being had to the accompanying drawings, forming a part thereof, in which—

Figure 1 represents a perspective view, and Fig. 2 is a cross-sectional view, of a pocket-book embodying my design.

The principal feature of the design consists in the marginal contour of the book, which simulates that of a barrel, said outline comprising two opposing side lines *a* of substan-

tially an elliptical character, their concaved sides facing inward, and upper and lower practically-straight lines *b*, which are merged at their ends in the side lines. The simulation of a barrel is further augmented by placing vertical lines *d* and transverse lines *d'* upon the face of the pocket-book, the arrangement of the lines being such that the spaces between them represent staves and hoops.

I claim—

The design for a pocket-book, substantially as shown and described.

JOHN HENKEL.
